UNITED STATES PATENT OFFICE.

FRIEDRICH EDMUND JOHANNIS BRUHN, OF HAMBURG, GERMANY.

MEANS FOR ADJUSTING HEAD-PIECES OF BEDSTEADS, &c.

SPECIFICATION forming part of Letters Patent No. 592,925, dated November 2, 1897.

Application filed February 25, 1896. Serial No. 580,625. (No model.)

To all whom it may concern:

Be it known that I, FRIEDRICH EDMUND JOHANNIS BRUHN, machinist, of 10th Stroh-hause, Hamburg, in the Empire of Germany, have invented Improved Means for Adjusting the Head-Pieces of Bedsteads, Couches, Sofas, or the Like, of which the following is a specification, reference being had therein to the accompanying drawings.

10 This invention relates to adjustable head-pieces for bedsteads, couches, sofas, or the like, which can be raised or lowered and fixed in any desired position in a very simple manner according to my present invention.

15 This invention is clearly illustrated in the accompanying drawings, in which—

Figure 1 is a plan view of a bedstead provided with the improved head-piece. Fig. 2 is a section on the line $x-x$, Fig. 1. Fig. 3 is 20 a portion of the section shown in Fig. 2, drawn to a larger scale; and Fig. 4 is an elevation of the lever and toothed-rack arrangement shown on a larger scale, looking in the direction of the arrows $y-y$, Fig. 2. Fig. 5 is a 25 tail view showing one of the retaining ratchets and pawls and the support for the latter.

In the frame A, which may be of iron or other suitable material, at the head of the bed, where the pillows are supported, an opening a^x is provided, in which a toothed rack a of curved form may work. This rack also passes between two side pieces or cheeks $b-b'$, which are fixed upon the frame A, and is adapted to be raised to any desired position 30 by means of the toothed wheel d , which is keyed or fixed onto the spindle c and is actuated by the one-armed lever t , arranged beside it on the spindle or axis C' .

On the spindle c' , which carries the toothed 40 wheel d' , and on both sides of this toothed wheel, ratchet-wheels e and f are cast or fixed, with one of which, f , a pawl k , pivotally mounted on the pin h , which is fixed on the cheek b' , engages, while a pawl l , fixed to the side 45 of the lever t by a pin t' , engages with the other ratchet-wheel e . By means of these two pawls the toothed wheel d is prevented from rotating, and consequently the toothed rack a is prevented from sliding down.

50 A guard or cover or flap o , which may be

made of bars, laths of iron, or other suitable material, between which wire-netting may be stretched, is hinged or pivotally arranged on the frame A—for instance, by means of the axis q , journaled in the lugs or mounts r —to receive the bolster or pillows. This guard or cover o is directly connected with the toothed rack a by any suitable means, such as hinges, and will thus be raised or lowered, and with it the bolster and pillows, according to the 55 position of the rack a .

In order to render it impossible for the flap o to come in contact with the gearing when the rack is allowed to slide down, the rack is 60 provided with a stop a' .

65 So as to permit of the pawls k and l being released from the two ratchet-wheels when desired and the head-piece o lowered each of the said pawls k and l is provided at the back with an eye or shank m , in which eye 70 or shank a cord or chain n is fastened, by means of which the pawls can be lifted, whereupon the rack a is free to slide down. If, on the contrary, it is desired to raise the head-piece, and with it, of course, the rack a , it is 75 only necessary to act upon the lever t by pulling on the cord n' , which is arranged on a guide-pulley under the bedstead or sofa and then carried to any convenient point—for instance, over it, as shown in the drawings—so 80 that in such case the occupant of the bedstead or couch can raise or lower the head part or flap o , as desired. When the cord n' is slackened, the arm t will fall, the pawl l slipping over its ratchet ready to be again 85 pulled up to raise the head-piece higher.

What I claim, and desire to secure by Letters Patent of the United States, is—

1. In an adjustable head-piece for bedsteads, couches, sofas or the like the combination with a hinged or pivoted flap such as o of a toothed rack such as a attached to said flap, a hinged lever such as t laterally arranged with respect to said rack a , a pawl operated by said lever, a ratchet engaged by the 90 pawl, a toothed wheel such as e connected with the ratchet and rack, means to impart motion from said wheel e to said rack a to raise and lower the flap o , a guide or pulley 95 at or near the foot of the couch, and a cord 100

extending from the lever over said guide, and back toward the head of the couch, substantially as described.

2. In an adjustable head-piece for bedsteads and other purposes, the combination of a hinged flap, a rack supporting the same, gearing engaging the rack, a ratchet and pawl holding said gearing from backward rotation, a lever, a pawl on the same also con-

nected with the gearing, a cord connected to with the lever, and a cord connected with both of said pawls, substantially as described.

In witness whereof I have hereunto set my hand in presence of two witnesses.

FRIEDRICH EDMUND JOHANNIS BRUHN.
